UNITED STATES PATENT OFFICE.

ARTHUR EDWIN LEIGH SCANES, OF ASHTON-ON-MERSEY, ENGLAND, ASSIGNOR TO THE BRITISH WESTINGHOUSE ELECTRIC AND MANUFACTURING COMPANY LIMITED, A COMPANY OF GREAT BRITAIN.

VALVE DEVICE.

1,347,411.

Specification of Letters Patent. Patented July 20, 1920.

Application filed November 25, 1918. Serial No. 264,030.

To all whom it may concern:

Be it known that I, ARTHUR EDWIN LEIGH SCANES, a subject of the King of Great Britain, and a resident of Ashton-on-Mersey, in the county of Chester, England, have invented a new and useful Improvement in Valve Devices, of which the following is a specification.

This invention relates to valve devices particularly applicable for use in connection with apparatus for exhausting air and non-condensable gases, and has for its object to provide improved apparatus of this character.

15 When exhausting apparatus such as a pump or ejector is used to evacuate a receiver it is frequently desirable to have a reflux or non-return valve situated between the exhausting apparatus and the receiver.

20 This valve has for its object to prevent the return of air or gases to the receiver in the event of the exhausting apparatus failing in its action. In valves of this description the weight of the valve is usually

25 balanced so as to minimize the pressure difference necessary to actuate the valve. Even in the most carefully made valves, however, friction cannot be entirely eliminated and when the pressure difference between the receiver and the evacuating apparatus is small, it may happen that there is a relatively large pressure drop through the valve due to incomplete opening, entailing a loss of efficiency.

35 In the present invention the improved valve device is provided with means for overcoming the effect of friction or of the spring or balance weight provided for normally holding the valve on its seat and resulting in incomplete opening of the valve especially when the difference of pressure on either side of the valve is small.

45 According to the invention a non-return valve in the suction pipe of an exhausting apparatus is connected with a piston working in a cylinder, one end of which is in communication with the space on the suction side of the valve and the other end of which is open to the atmosphere or communicates with a source of pressure above atmospheric, the piston being so connected to the valve as to assist in the opening thereof when the pressure on the suction side is re-

duced below that on the other side of the piston.

55

In order that the nature of the invention may be clearly understood one method of carrying the same into effect will now be described with reference to the accompanying drawing which is a sectional elevation 60 of an improved valve device constructed in accordance with the invention.

The suction pipe 1 of an air or gas exhausting apparatus such as a pump or ejector is provided with a seat 2 and a 65 coöperating valve 3 of the "mushroom" type which is held upon said seat by means of a balance weight 4 acting through a lever 5 which is pivoted to the stem 6 of the valve. The seat 2 may be provided with wings 7 70 supporting a guide 8 for the valve stem. The valve stem is enlarged at one part to form a piston 9 which coöperates with a cylinder 10 which is conveniently formed by an inward extension of the suction pipe. Additional support may be given to the cylinder by means of the web 11.

75 The valve stem 6 is formed hollow and communicates on the one hand by means of a port 12 with the space in the cylinder 10 80 below the piston 9, and on the other hand at the bottom of the stem with the space 13 on the suction side of the valve, that is on the side nearest the pump or ejector. The other end of the cylinder 10, that is to say 85 the space on the upper side of the piston 9, is open to the atmosphere and is provided with a liquid seal 14.

90 The operation of the device is as follows:—

Before the exhausting device is started and assuming that there is atmospheric pressure throughout the system, the balance weight 4 will keep the valve 3 on its seat 2. On starting the exhausting device 95 a drop in pressure will be produced on the suction side 13 of the valve 3 and in the lower end of the cylinder 10 which is in communication with this space 13 through the hollow valve stem 6. The pressure on the upper side of the valve being atmospheric the valve will open and the pressure on the upper side will accordingly be reduced. Consequently the difference of pressure on the two sides of the valve will diminish and may not be sufficient to open the 100 105

valve fully against the lifting action of the balance weight 4. The pressure on the upper side of the piston 9, however, is not reduced by the opening of the valve and the 5 difference in pressure on the two sides of said piston will be sufficient to cause the valve to move to its full open position. Should the exhausting device fail in its action and the flow of air or gas tend to re-10 verse in direction the pressure difference across the valve will diminish still more and the difference in pressure on the two sides of the piston 9 will also be reduced so that the action of the balance weight 4 will be 15 sufficient to close the valve.

Various modifications may be made in the construction which is not limited to that shown in the drawing. A spring may be used in place of the balance weight and the 20 upper side of the piston 9 may be exposed to a source of higher pressure than that of the atmosphere, such as for instance that of a supply of steam or water.

I claim as my invention:

25 1. In the suction pipe of an air or gas exhausting device, the combination with a non-return valve adapted to be closed by an excess of pressure on the suction or pump side thereof, means adapted to positively 30 close said valve, a cylinder, a piston cooperating therewith, the space in the cylinder on one side of the piston being in communication with the suction pipe on the suction or pump side of the valve, and the space 35 in the cylinder on the other side of said

piston being in communication with the atmosphere or a source of pressure above atmospheric, said piston being so connected with the valve as to assist in the opening thereof when the pressure on the suction side of said piston is reduced below that on the other side of said piston.

2. In an air or gas-exhausting device, the combination with a non-return valve adapted to be closed by an excess of pressure on 4 the suction or pump side of the device and having a stem provided with a piston, and means adapted to positively close it, of a cylinder for said piston having a permanently-open connection with the suction pipe 5 on the suction or pump side of the valve at one end of the piston and subjected to at least atmospheric pressure at the other end of the piston.

3. In an air or gas-exhausting device, the 5 combination with a non-return valve adapted to open toward the suction or pump side and having a stem provided with a piston and means tending to positively hold it to its seat, of a cylinder for said piston provided with connections whereby one end of the piston is subjected to at least atmospheric pressure and the other end is subjected to the fluid-pressure conditions on the suction or pump side of the valve. 6

In testimony whereof I have hereunto subscribed my name this twenty-second day of October, 1918.

ARTHUR EDWIN LEIGH SCANES.
